UNITED STATES PATENT OFFICE

THOMAS JOSEPH FOWLER, OF CHICAGO, ILLINOIS

COMPRESSOR HOUSING

Application filed October 9, 1929, Serial No. 398,284. Renewed April 6, 1932.

This invention relates to refrigerating machinery and, more particularly, to a compressor and driving means therefor.

The invention provides a compressor for a mechanical refrigerator which is built in a single unit with a driving motor and is so constructed as to eliminate the necessity for stuffing boxes and external driving connections.

10 According to one form of the invention, two compressor cylinders are mounted on opposite sides of the motor and are directly driven from the motor shaft, the compressor cylinders and the motor being enclosed in a single unitary casing. The casing includes means for equalizing the gas pressure and the oil level between the two cylinders and for preventing oil and refrigerating gases from interfering with the operation of the 15 motor.

The invention is particularly applicable to small refrigerating units and is sufficiently compact to be conveniently assembled as a part of such units.

20 The invention also consists in certain new and original features of construction and combinations of parts hereinafter set forth and claimed.

25 Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawing forming a part thereof, in which

Fig. 1 is a side elevation partly in section 30 of the compressor units and driving motor; and

Fig. 2 is a sectional view of a modified form of oil ring which may be used for preventing oil from entering the motor compartment.

Like reference characters denote like parts in the several figures of the drawing.

In the following description and in the claims parts will be identified by specific 45 names for convenience, but they are intended

to be as generic in their application to similar parts as the art will permit.

Referring to the drawing more in detail, the invention is shown as applied to a compressor unit including a motor 10, having a casing which is formed with a central section 11 provided with feet 12 or other suitable means for attachment to a base member 13. End sections 14 of the casing are provided with a motor section 15 which, in conjunction with central section 11, forms a complete closure for motor 10, and a compressor section comprising a crank case 16 and a cylinder housing 17. Intermediate motor section 15 and crank case 16 is a bearing support 18 and an annular space 19 for a purpose to be described. Motor 10 is preferably of the induction type which requires no commutator or brushes. The use of a brushless motor is important in a compressor of this 70 type as the oil and refrigerating gases cause deterioration of the brushes and a spark in contact with the gas mixture might cause an explosion.

Motor shaft 20 is journalled in bearings 21 which are secured in bearing support 18 of the casing and terminates at each end in an eccentric 22 to which a connecting rod 23 is secured by suitable means, such as strap 24. The particular means for connecting the connecting rod to the eccentric on the motor shaft is not set forth in detail since it is evident that any standard form of construction may be employed.

Motor shaft 20 is provided with an oil ring 25 located in alignment with an aperture 26 adjacent bearing support 18 in section 14 of the casing which communicates with annular space 19. An outwardly extending flange 27 receives oil which is discharged by ring 25 and directs the same into crank case 16. Web 27 also prevents direct passage of oil from said crank case into said annular space 19.

An oil pipe 30 is connected to a pair of 95 nipples 31 which are inserted in suitable bores 32 in the bottom of crank cases 16 for providing a direct passage for the oil between the two crank cases and equalizing the oil level therein.

Crank cases 16 are closed by covers 33 which are secured thereto by any suitable means such as bolts 34. Said covers may be provided with inspection holes 35 which are normally closed by plugs 36 and are provided with oil holes 37 closed by plugs 38.

A cylinder bushing or liner 40 is secured in cylinder housing 17 in any suitable manner as by pads 41 and flanges 57, which may be cast integrally with said housing. Piston 42 is attached to connecting rod 23 by suitable means and is provided with suitable rings 44 which are seated in bushing 40. Ports 45 are formed in pads 41 for the purpose to be described.

A plate 46 is secured between housing 17 and cylinder head 47 and is provided with apertures 48 through which the compressed gases are discharged. Valve plate 49 is normally seated over said apertures and is held in engagement therewith by spring 50 which is seated on stud 51. Discharge pipe 52 is associated with cylinder head 47 in any convenient manner as through a port 53 in the top thereof. Cylinder head 47 may be secured to housing 17 by bolts 54.

Bushing 40 is provided with an intake port 55 which communicates with a recess 56 formed in housing 17 between pad 41 and flange 57. Said recess may communicate with an intake pipe 58 by which the low pressure gases are applied to the cylinder.

In the modified form of oil seal shown in Fig. 2, a stationary flange 60 is secured in recess 26 and contacts with shaft 20 of motor 10. Stationary washer 61 is connected with flange 60 by metallic bellows 62 and is held by spring 63 in engagement with floating washer 64. Said washer 64 seats against a shoulder 65 on motor shaft 20 and prevents direct passage of oil along said shaft. An oil hole 66 may be formed in bearing section 18 of the housing in communication with bearing 21 for directing oil onto the motor shaft.

In the above described apparatus the two compressor cylinders are integrally mounted in the same housing with motor 10 and the pistons are directly driven by shaft 20 by means of eccentrics 22. The oil in the crank cases is prevented by the oil seal, shown in Fig. 1 as ring 25 and in Fig. 2 as the metallic bellows, from entering the motor compartment. The gas pressure in the crank cases is equalized through ports 45, recesses 56 and pipe 58 and the oil level is equalized through pipe 30 thereby eliminating any tendency of the low pressure gases to force their way from one crank case to the other through the motor compartment. Ports 45 also allow oil to return to crank case 16 and relieve any surplus gas that may accumulate in the crank case. Since there is no active flow of gas through the crank case there will be only a small amount of gas displaced

through ports 45 during normal operation.

It is to be noted that since no moving parts extend outside of the motor housing there is no necessity for utilizing packing or other means for preventing escape of gases to the outside. The device is accordingly compact and may be shipped and installed as a unit without requiring adjustment or any special skill for the installation.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. In combination, a brushless motor, a housing therefor having a bearing support, a motor shaft journaled in said support, said housing having an annular recess adjacent said support and an oil ring carried by said shaft in alignment with said recess whereby oil is prevented from creeping along said shaft and entering said motor, and is discharged into said recess.

2. In combination, a brushless motor, a housing therefor having a bearing support, a motor shaft journaled in said support, said housing having an annular recess adjacent said support, an oil ring carried by said shaft in alignment with said recess whereby oil is prevented from creeping along said shaft and entering said motor, a compressor cylinder having a crank case integrally formed with said motor housing, and a downwardly extending web formed on said bearing support to prevent passage of oil from said crank case into said recess.

3. In combination, a brushless electric motor, a pair of compressor cylinders associated therewith, a unitary housing for said cylinders and said motor, each of said cylinders having a crank case associated therewith, said motor having a shaft extending into said crank case, said cylinders having a gas intake passage and a supply pipe interconnecting said passages, and a port extending between each said passage and crank case whereby gas pressure in said crank case is equalized.

4. In combination, a brushless electric motor, a pair of compressor cylinders associated therewith, a unitary housing for said cylinders and said motor, each of said cylinders having a crank case associated therewith, said motor having a shaft extending into said crank cases, said cylinders having a gas intake passage and a supply pipe interconnecting said passages, a port extending between each said passage and crank case whereby gas pressure in said crank case is equalized, and an oil pipe interconnecting the

lower parts of said crank cases for equalizing the oil level therein.

5. In combination, an electric motor, a housing therefor having a bearing support and a crank case, a motor shaft journalled in said support, said housing having an annular recess adjacent said support, an oil ring carried by said shaft in alignment with said recess whereby oil is discharged in said 10 recess and is prevented from entering said motor, said recess having an opening into said crank case whereby the oil is returned thereto.

6. A compressor unit comprising an electric motor having a shaft, a housing for said motor having means rotatably supporting said shaft, a pair of compressor cylinders and crank cases mounted at opposite ends of said shaft and having pistons operated by 20 said shaft, said cylinders and said crank cases being formed as a continuation of said housing and providing a complete enclosure through which no moving part extends, means for preventing passage of oil from said 25 crank cases along said shaft into said motor housing, said means also retarding passage of gases into said motor housing, and means external of said motor housing for equalizing the gas pressures in said crank cases whereby 30 to further retard passage of said gases through said motor housing.

7. A compressor unit comprising an electric motor having a shaft, a housing for said motor having means rotatably supporting said 35 shaft, a pair of compressor cylinders and crank cases mounted at opposite ends of said shaft and having pistons operated by said shaft, said cylinders and said crank cases being formed as a continuation of said housing 40 and providing a complete enclosure through which no moving part extends, means for preventing passage of oil from said crank cases along said shaft into said motor housing, said means also retarding passage of 45 gases into said motor housing, means external of said motor housing for equalizing the gas pressures in said crank cases whereby to further retard passage of said gases through said motor housing, and means external of 50 said motor housing for equalizing the oil level in said crank cases.

8. A compressor unit comprising an electric motor having a shaft, a housing for said motor having means rotatably supporting 55 said shaft, a pair of compressor cylinders and crank cases mounted at opposite ends of said shaft and having pistons operated by said shaft, said cylinders and said crank cases being formed as a continuation of said housing 60 and providing a complete enclosure through which no moving part extends, means for preventing passage of oil from said crank cases along said shaft into said motor housing, said means also retarding passage of gases 65 into said motor housing, means external of

said motor housing for equalizing the gas pressures in said crank cases whereby to further retard passage of said gases through said motor housing, and an oil pipe interconnecting said crank cases below the normal oil level 70 therein for equalizing the oil level in said crank cases.

9. A compressor unit comprising an electric motor having a shaft, a housing for said motor having means rotatably supporting 75 said shaft, a pair of compressor cylinders and crank cases mounted at opposite ends of said shaft and having pistons operated by said shaft, said cylinders and said crank cases being formed as a continuation of said housing 80 and providing a complete enclosure through which no moving part extends, means for preventing passage of oil from said crank cases along said shaft into said motor housing, said means also retarding passage of 85 gases into said motor housing, a pipe interconnecting said cylinders and communicating with said crank cases for equalizing the gas pressures in said crank cases whereby to further retard passage of said gases through 90 said motor housing.

In testimony whereof I have hereunto set my hand.
